UNITED STATES PATENT OFFICE.

EMANUEL L. BUXXBAUM, OF CHICAGO, ILLINOIS.

SIGN HAVING DETACHABLE DISPLAY ELEMENTS.

Application filed September 15, 1924. Serial No. 737,704.

To all whom it may concern:

Be it known that I, EMANUEL L. BUXXBAUM, a citizen of the United States, residing in Chicago, county of Cook, State of Illinois, have invented a certain new and useful Improvement in Signs Having Detachable Display Elements, and declare the following to be a full, clear, and exact description of the same, such as will enable others skilled in the art to which it pertains to make and use the same, reference being had to the accompanying drawings, which form a part of this specification.

It is common practice in offices, banks and the like containing numerous people to provide each desk or cage with a sign bearing the name of the occupant. These signs must not only be neat but they must be substantial and have the appearance of permanency, and it has therefore been customary to make them out of metal, each name plate being an individual casting of bronze or other suitable material. Thus the better signs or plates have been quite expensive.

The object of the present invention is to produce a simple and novel sign or display device that will permit the use of thin embossed metal for carrying words, names or display devices of any kind, in such a manner that the structure as a whole will have the same degree of solidity and permanency and be just as neat and attractive as the old solid cast signs, but will be much less expensive than the latter.

The various features of novelty whereby my invention is characterized will herein-after be pointed out with particularity in the claims; but for a full understanding of my invention and of its objects and advantages, reference may be had to the following detailed description taken in connection with the accompanying drawing, wherein:

Figure 1 is a front elevation of a desk sign arranged in accordance with the present invention; Fig. 2 is an end view of the device shown in Fig. 1; Fig. 3 is a rear view of the device, on an enlarged scale; Fig. 4 is a section taken approximately on line 4-4 of Fig. 3; Fig. 5 is a view similar to Fig. 3, showing only a fragment of the device, one of the clamps being open and one of the clamp-engaging studs being in section; and Fig. 6 is a view similar to Fig. 1, showing a fragment of a modified construction.

Referring to the drawing, 1 represents a flat plate having a long rectangular opening 2 go through the same; this opening being adapted to contain the name or other matter to be displayed and the plate thus serving as a frame surrounding such matter. As best shown in Fig. 4, there is a depression 3 in the rear of the member 1 surrounding the slot or opening; this depression having a depth equal to the thickness of a sheet of metal 4 that is to carry the name or other matter to be displayed. The member 4 is cut to such a size and shape that it will fit in the recess in the rear face of the supporting plate, and the letters 5 or other things to be displayed, are embossed in the sheet metal so as to project forwardly through the opening or slot in the supporting plate. The sheet metal is to fragile to retain its shape without being solidly reinforced, and I have therefore provided a strong back plate 6, larger than the sheet metal plate so that the latter is completely concealed when the back plate is laid over the same. On the rear side of the member 1 are two pairs of headed studs 7, 7 and 8, 8, the studs of each pair lying on opposite sides of the slot or opening, and the two pairs being spaced apart lengthwise of the slot. The back plate is preferably made somewhat wider than the distance between the studs of each pair, and is provided at its edges with notches 9 but permitted to be placed between the studs. On the rear side of the back plate are two clamping bars 10 and 11, each pivoted at the middle, as indicated at 12, to the back plate, and having its ends beveled as indicated at 13. The locking bars are made of such length that when they are swung so as to lie approximately at right angles to the long axis of the back plate, the beveled end edges become wedged underneath the heads on the studs and thus clamp the back plate firmly against the front plate or frame. The back plate not only holds the display plate in place but it forms a solid backing for the latter and gives thereto a rigidity and a degree of permanency comparable to that possessed by a heavy solid cast plate.

If desired, the back plate may initially be bowed somewhat as shown in dotted lines in Fig. 4, so that when the ends are drawn against the frame, the central portion will exert a spring pressure on the name plate, thus insuring that the name plate will be solidly backed throughout its length.

If desired, instead of making the name plate or display plate in a single piece, it may be made out of a plurality of pieces arranged side by side. Such a construction is shown in Fig. 6 in which there are a large number of small pieces or panels 14, each bearing a letter or other device, or being simply a blank to serve as a spacer. By making each letter or other device in the form of a separate piece, any desired name or legend, within the capacity of the opening in the supporting frame, may be assembled out of stock pieces.

The front plate or frame may be supported in a usual or suitable way. If it is intended as a desk sign, it may be provided with supporting feet in the form of wings 15 produced by bending the ends of the frame or plate rearwardly; the lower marginal portions or corners of the wings being cut away at the angle necessary to permit the front face of the sign to be positioned at the desired angle.

Each clamping bar may be provided with two ears or projections 17 rising from opposed long edges on opposite sides of the pivot. A person desiring to unlock or lock the device can easily turn the clamping bars by grasping the two ears of each between a thumb and forefinger; or, if a bar should happen to be wedged very tightly, a pencil or paper cutter or other stiff element can be inserted between the ears and used as a lever to turn the bar.

While I have illustrated and described with particularity only a single preferred form of my invention, including a slight modification, I do not desire to be limited

to the exact structural details thus illustrated and described; but intend to cover all forms and arrangements coming within the definitions of my invention constituting the appended claims.

I claim:

1. A stiff metal front plate having a sight opening, the rear face of the plate being depressed around said opening, a sign made of sheet metal fitting in said depression and having embossed matter projecting into said opening, headed studs on the rear of said front plate adjacent to said depression, a heavy back plate overlying said sign in the space between said studs, and beveled locking members movably mounted on said back plate in positions to be engaged under the heads of said studs to press the back plate firmly against the front plate.

2. A stiff metal front plate having a sight opening, the rear face of the plate being depressed around said opening, a sign made of sheet metal fitting in said depression and having embossed matter projecting into said opening, headed studs on the rear of said front plate adjacent to said depression, a heavy back plate overlying said sign in the space between said studs, beveled locking members movably mounted on said back plate in positions to be engaged under the heads of said studs to press the back plate firmly against the front plate, and ears rising from each of said locking members and serving as finger pieces by which said members may be moved.

In testimony whereof, I sign the specification.

EMANUEL L. BUXTBAUM.
